(57) **CLAIM**

The ornamental design for an edge-lit fin, as shown and described.

DESCRIPTION

FIG. 1 is a front perspective view of an edge-lit fin showing the new design;

FIG. 2 is a left elevational view thereof, a right elevational view being a mirror image thereof;

FIG. 3 is a back elevational view thereof;

FIG. 4 is a front elevational view thereof;

FIG. 5 is a top plan view thereof;

FIG. 6 is a bottom plan view thereof; and,

FIG. 7 is a rear perspective view thereof.

The broken lines are for the purposes of illustrating portions of the edge-lit fin or the environmental structure that form no part of the claimed design.
